UNITED STATES PATENT OFFICE.

WILLIAM D. BARDET, OF TRENTON, TENNESSEE.

BEER-COOLER.

SPECIFICATION forming part of Letters Patent No. 241,776, dated May 24, 1881.

Application filed July 31, 1880. (No model.)

To all whom it may concern:

Be it known that I, WILLIAM DICKSON BARDET, a citizen of the United States, residing at Trenton, in the county of Gibson and State 5 of Tennessee, have invented new and useful Improvements in Beer-Coolers, of which the following is a specification.

My invention relates to that class of beer-coolers in which the beer to be dispensed passes 10 through a coil of pipe surrounded by ice within an inclosed chamber.

My said invention will be hereinafter particularly set forth, and specified in the claims.

Briefly, I place an ice-holding basket composed of a top ring, beer-conducting pipes, and a bottom chamber, within a water-cooler inclosed within a covering-vessel, having an intervening packing of non-conducting material, whereby cold beer may be drawn off and ice 20 water dispensed also. The special means necessary to such a result will be hereinafter described and claimed, and are shown in the accompanying drawings, in which—

Figure 1 represents a vertical section; Fig. 25 2, a similar section on the line xx of Fig. 1, and Fig. 3 a perspective view of the ice-basket removed.

The casing A is preferably cylindrical in form, and incloses a covered cylinder, B, which acts 30 as an ice-water receptacle, the bottom of which does not touch the bottom of the case A, but is supported therein by feet. Around the cylinder B, and between it and the case A, there is a non-conducting packing, a, of sawdust or 35 other cheap material.

Within the cylinder B, I hang upon brackets c upon the inner side of said cylinder, and near its top, an ice-basket, C, composed of an annular tube, d, and tubes e connecting therewith, and downwardly curving to a shallow 40 central circular receptacle or chamber, D, the top of which extends above the plane of the discharge-exits of the tubes e, so as to form a chamber for the cooled beer, and a reservoir 45 for the collection and storage of the beer, and to permit of room for carbonic-acid-gas collection, so that there may be a proper discharge-force. This chamber D is pierced by the beer-discharge pipe E at the bottom, and so also 50 the top annular tube, d, by the receiving-pipe F from the barrel. As the basket rests upon

the brackets c it may be removed daily for the purpose of cleaning the bottom of the water-vessel or inner cylinder, B, although if clean ice be used such frequency of cleaning is un- 55 necessary.

Stay-pieces f center the water-cooler within the inclosing-case.

At any suitable point the annular tube d is pierced by a pipe, F, connecting with a pipe-coupling, h, from the beer-barrel, and the contents of the beer-barrel are discharged into this annular tube d by force of gravity or the usual pump-power. As the basket C, hitherto described, contains the ice, the beer flows through 60 the said annulus and the downwardly-curving tubes e to the receptacle D, which latter is pierced at any point by the beer-faucet pipe E, which latter is protected and guarded through the intervening non-conducting material by a 65 pipe-sleeve, i; so, also, is the connection of the beer-barrel pipe guarded by a similar pipe-sleeve guard, k, as shown. In making these connections the pipes are screwed into threaded connections l, and one being secured the other 70 matches. So, also, similar connections and sleeves m m' provide for the discharge of ice-water from the cooler B, and the discharge-pipe S for ice-water may be changed from the one side to the other by suitable coupling-connections o, so as to accommodate the apparatus to 75 the position of the counter.

The ice-basket is held near the top, so as to permit of plenty of room for ice-water.

It will be seen that a great advantage of my 80 invention consists in the saving of ice, as fourteen pounds will last all day.

In removing the basket it is only necessary to uncouple the barrel-connecting and draft pipes. 90

The connections with the water-chamber are made water-tight by packing-nuts o' secured from the inside of said chamber, as shown in the detail, Fig. 4.

I claim—

1. In a beer-cooler, the removable ice-basket C, composed of the annular top tube, d, the bottom reservoir-chamber, D, of less diameter than said top tube, and the tubes e, connecting and communicating with said annular top tube 100 and bottom reservoir-chamber, substantially as described, for the purpose specified.

2. In a beer-cooling apparatus, in which a water-cooler is surrounded by a non-conducting inclosing-case, the ice-basket composed of beer-conducting tubes suspended above the bottom of said water-cooler, substantially as and for the purpose set forth.
3. In a beer-cooler, the combination of the suspended basket C, constructed substantially as shown and described, with the covered casing A, the covered water-cooler B, and the pipes E, F, and S, the said casing being provided with non-conducting material surrounding said cool-

er, and the said pipes being provided with protecting-sleeves passing through said non-conducting material, substantially as shown and 15 described.

In testimony whereof I have hereunto set my hand in the presence of two subscribing witnesses.

WILLIAM DICKSON BARDET.
